UNITED STATES PATENT OFFICE

DOROTHY LONG, OF NEW YORK, N. Y., ASSIGNOR TO FRANKLIN SIMON & COMPANY, INC., OF NEW YORK, N. Y., A CORPORATION OF NEW YORK

DESIGN FOR AN ENSEMBLE DRESS

Application filed January 9, 1932. Serial No. 42,432. Term of patent 3½ years.

To all whom it may concern:

Be it known that I, DOROTHY LONG, a citizen of the United States, and a resident of New York, borough of Manhattan, in the county of New York and State of New York, have invented the new, original, and ornamental Design for an Ensemble Dress, of which the following is a specification.

Reference is had to the accompanying drawings forming part thereof, wherein—rear of the coat portion being plain except for the ornamental figures in the material which are identical with those in the front, the rear of the dress section being shown in Figure 2.

I claim:—

The ornamental design for an ensemble dress, substantially as shown and described.

DOROTHY LONG.
